UNITED STATES PATENT OFFICE.

HARVEY L. HARRIS, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

TELEPHONE-EXCHANGE SYSTEM.

1,324,739.

Specification of Letters Patent.

Patented Dec. 9, 1919.

Application filed November 15, 1917. Serial No. 202,122.

To all whom it may concern:

Be it known that I, HARVEY L. HARRIS, a citizen of the United States, residing at Rochester, in the county of Monroe and

5 State of New York, have invented certain new and useful Improvements in Telephone-Exchange Systems; and I do hereby declare the following to be a full, clear, and exact description of the invention, such as will 10 enable others skilled in the art to which it appertains to make and use the invention.

My invention relates to telephone systems, and more particularly to systems in which an associated multiple lamp is employed—that is, a system in which the call of a subscriber is indicated at a plurality of positions or before a plurality of operators, and in which a call may be answered by any operator.

20 One of the objects of my invention is to provide improved means to indicate to operators who answer a call the fact that it has already been answered, when that is the fact. I aim to indicate this in a suitable and 25 adequate manner, and to combine this feature with other desirable features, in such a way, as to enable the apparatus to be installed without prohibitive complications or expense.

30 It is another object of my invention to accomplish the aforesaid object without requiring the actuation of any movable apparatus in the subsequent answering operator's cord circuit. I accomplish this by having 35 the cord circuit of the first answering operator apply a tone signal to the local operating strand of the line circuit of the calling subscriber in such a way, that any subsequent answering operator will hear the 40 tone in her telephone receiver without requiring the actuation of such a subsequent answering operator's supervisory relay.

Other objects of my invention and the invention itself will probably be better understood from a description of an embodiment 45 of my invention, reference being made to the attached drawings in which I show a calling telephone at A connected on a line L₁, leading to a central exchange and terminating thereat in multiple jacks J₁ and J₂. Associated with these multiple jacks are signal lamps S₁ and S₂, each connected in multiple, and each adapted to be operated when the telephone at A is operatively connected

to the line L₁ by the closing of contacts c of 55 the hookswitch; a line in addition to be called is shown at L₂ having a telephone B connected thereto.

At the central station at C I show an operator's answering link circuit, here shown 60 in the form of a cord circuit, and at D I show a like cord circuit of another operator located at a different operator's position.

The cord circuits C and D are alike in all respects, and have associated each therewith 65 operator's telephone apparatus as at O₁ for the cord circuit C, and O₂ for the cord circuit D. Only a portion of the operator's circuit O₂ is illustrated in the drawing, it being understood that the balance of this operator's circuit is the same as that of the operator's circuit shown at O₁.

The cord circuit C terminates in an answering plug P₁, adapted to coöperate with the multiple jack J₁ of the calling line 75 to establish a connection therewith. Likewise the answering plug P₂ of the cord circuit D is adapted to coöperate with the multiple jack J₂ of the calling line to establish a connection therewith.

A relay K is shown in each of the cord circuits adapted when operated to connect the respective operators' telephone sets to the particular cord circuit. This relay is automatically operated whenever a call is 85 answered. Like relays F₁ and F₂ are also shown as associated with the cord circuits C and D respectively. The functions of these relays will be later apparent from the description of the invention which follows. 90

The third strand controlling relays E are shown at the calling ends of the cord circuits, and adapted to operate whenever a calling plug, such as P₃ and P₄ of the cord circuits is inserted in a jack, such as J₃ or J₄ 95 of a called line.

Perhaps my system and its functions will be better understood from a description of the operation of the same as follows:—

Assume that the subscriber A makes a call 100 by removing his receiver from the hook and closing the contacts of his hookswitch c, a circuit will be completed in the usual manner for the line relay A which will operate closing its contacts which are in a circuit 105 including a source of current M, and the signal lamps S₁ and S₂. This signal will thereupon be lighted indicating to the opera-

tor whose set is shown at O_1 and to the operator a portion of whose set is shown at O_2 alike, that a call exists on the line L_1 . Each operator endeavoring to answer this call will 5 insert the answering plug of their respective cord circuits into one of the multiple jacks J_1 or J_2 adjacent to their positions.

One of the operators will make the connection of the plug and jack switch before 10 the other. The one first to make the connection will have her operator's set operatively connected to the telephone line, and the other operator will not have her operator's set connected to the line. The first operator 15 will then go ahead and converse, from the subscriber learn the number of the desired telephone, and complete the connection by inserting the calling plug of her cord circuit into the called line jack. Assuming that 20 the operator whose set is shown at O_1 is the connected operator, that is, the one who first made the plug and jack switch connection to the line, the operation of the apparatus in her cord circuit involved is, briefly, as follows:—Upon the plug and jack switch connection being made, the cut-off relay of the 25 line circuit c will be operated over a circuit leading from the ground pole of battery, the winding of the cut-off relay, the coöperating 30 contact of the plug and jack switch, circuit conductor 2, the high resistance winding R of the induction coil I , the operating winding f of the relay F_1 , the circuit conductor 3, leading to the negative pole of the source of 35 current M , which it will be understood may be common to the exchange, this circuit being completed by the plug and jack switch P_1, J_1 before the operation of the plug and 40 jack switch P_2, J_2 . All of the current, therefore, from the cut-off relay c from the said source of current will flow through the winding f of the relay F_1 , and the relay is adjusted to operate over 45 the resistance R under influence of such an amount of current as would flow under these conditions. The relay F_1 operating will 50 close its contacts 4, shunting the resistance winding R of the induction coil I , and reducing thereby the resistance of the circuit leading 55 from the conductor 2 to the source of current M , which includes the winding f of the relay F_1 .

The contacts 5 of the relay F_1 in the circuit of the source of tone current T shown at 60 the bottom of the drawing will now be closed. The contacts 6 of the relay F_1 will also be closed completing a circuit including the source of current M , the winding of the operator's listening relay K , and the normally made contacts 7 of the relay E to operate the relay K which when operated will connect the operator's telephone O_1 by its conductors 8 and 9 to the talking strands of the cord circuit which are at the time connected to the telephone line by the plug and 65

jack switch; the connection being made through contacts 12 and 13 of the listening relay K . The normally made contacts 14 of the relay K will now be broken for a purpose later to be described.

Now, assuming that the operator O_2 later connecting the cord circuit D to the line by means of the plug and jack switch P_2, J_2 , attempts to answer the call of the subscriber A which is being answered by the operator 70 O_1 . Such an attempt will be unsuccessful because the relay F_2 will not be operative for the reason that the resistance of its operating circuit, including the resistance of its operating winding f 75 added to the resistance of the winding R of the induction coil I_2 which is in circuit with the winding f , is of considerably more resistance than the winding f of the relay F_1 with which it is now placed in multiple circuit and the adjustment of the relay F_2 being marginal, it will not with the amount of current flow through its winding f attract its armatures and will remain inoperative. Therefore, the second operator attempting 80 to answer the call will not have her set connected in conversational circuit with the calling line, due to the failure of the relay F_2 to operate which is required to operate in order to operate the listening relay K of 85 the cord circuit.

Prior to my invention, systems have been devised to accomplish this failure to connect the second operator's set to a calling line under the above conditions. I am aware also 90 that a system has been devised whereby apparatus involving the moving contacts of a supervisory relay in the second connected operator's cord circuit applied an audible tone to the operator's set to apprise her that 95 her attempt to answer the call was unsuccessful, because of the more rapid answering of the call by another operator.

In my present invention I likewise aim to 100 apply an audible tone to the unsuccessful operator's telephone set, but I do not depend upon the supervisory relay of the second connected cord circuit to operate, since this 105 it may fail to do when connected to lines of high resistance; due to the shunting effect of the first connected cord circuit supervisory relay. I, therefore, as will be now shown, cause the audible tone to be applied by the actuation of apparatus in the successful or first connected cord circuit, the same being 110 applied to a local operating strand of the line extended between the various operators' positions and extended to the second connected operator's telephone set by means of the plug and jack switch of the second connected cord circuit.

In describing the operation of the relay F_1 of the cord circuit C which is being described as the first connected cord circuit, I 115 describe contacts 5 in the source of tone cur- 120

rent T as being closed. This tone circuit is therefore be caused to flow over the operator's receiver T producing a tone therein only operatively completed to perform its functions when the second connected cord which will be heard by the operator, and in circuit is connected to the line by means of its plug and jack switch, as the plug and jack switch P_2, J_2 , in which case the completed circuit involving this tone circuit T is 70 answered by some other operator, in this case by the operator whose set is shown at O_1 .

as follows:—From the negative pole of the said source of current, through intermittent contacts of the interrupter N, and the primary winding of the transformer T to the ground pole of battery. This will cause an intermittent flow of current through the primary winding of this transformer, inducing 75 the fluctuating current in the secondary winding of this transformer T which is considered as the common source of tone current for the exchange. The circuit of this tone current induced in the secondary winding is 80 traced as follows:—From the ground pole of battery, the secondary winding of the transformer T, the contacts 5 of the relay F₁, the normal contacts 15 of the relay E, circuit conductor 17, the tone winding g of the relay F₁, and from thence returned to ground. 85

The flow of current over this circuit will in turn induce a rapidly fluctuating flow of current in the operating winding f of the relay F₁, the two windings of the said relay having an inductive effect, one of the other, and the tone current is therefore created in the winding f , and complete circuit therefore is traced as follows:—From the negative pole of the source of current M, circuit conductor 3, the winding f of the relay F₁, the now closed contacts 4 thereof, circuit conductor 2, coöperating contacts of the plug and jack switch P_1, J_1 , inter-multiple jack conductor 16, coöperating contacts of the plug and jack switch P_2, J_2 , circuit conductor 2 in the cord circuit D, the winding R of the induction coil I₂, the winding f of the relay F₂, circuit conductor 18, leading back 90 to the negative pole of the source of current M. This circuit being completed fluctuating tone current will flow over the same and through the included winding R of the induction coil I₂, inducing a like tone current 95 in the secondary winding thereof R₂. This induced tone current flows in a circuit traced from the ground pole of battery, the winding R₂, normal contacts 19 of the relay K, circuit conductor 20 common to a plurality 100 of cord circuits and leading to the operator's set O₂ where it is completed through a winding o of the operator's induction coil Z, the said winding being connected at its other terminal to the ground pole of battery. Current flowing over this circuit including the 105 winding o will induce a like tone current in the winding o₂ of the operator's induction coil, which winding is connected through the resistance coil y across the terminals of 110 the operator's receiver T. Tone current will

It is apparent in the system of my invention any practical number of operators attempting to answer the same call after the 75 call has been answered by a first operator, will be unsuccessful in their attempts and will receive this tone current, the applying of the tone current not depending upon any movable parts in each of the cord circuits, 80 but being applied by a relay in the first connected cord circuit will so operate prior to the connection of a second cord circuit to a circuit of the line. In this way I do away with marginal adjustments of the supervisory relays in the cord circuits. 85

While I have illustrated and described the operation of only two cord circuits, it will be understood that in practice in most cases each operator will have associated with her 90 telephone set a plurality of cord circuits, such as illustrated and described.

I am aware that other embodiments of my invention may be devised for accomplishing the aforesaid object involving numerous and extensive departures from the express disclosure herein attained, but what I claim as my invention is limited only by the scope of the following claims. 95

1. In a telephone system, the combination 100 with a telephone line extended from a substation and terminating at a main station in a plurality of switching terminals, of a plurality of operators' link circuits at the exchange having answering contacts, each 105 adapted to be connected with a set of the said switching terminals, means in a first named circuit to associate a source of tone current with interconnected contacts of the said switching terminals, means responsive 110 to the operation of the said tone associating means to cause the connection of the associated operator's set to the talking conductors of the said link circuit, and means responsive to the connection of the said first 115 connected link circuit to the switching terminals of the calling telephone line to disable the tone associating means of a second connected link circuit to permit the flow of the said tone current through the operator's set for the said link circuit, said operator's connecting means of the second connected cord circuit being under the control 120 of the said disabling means.

2. In a telephone system, the combination 125 with a telephone line leading from a substation to an exchange, of multiple switchboard contacts for the said line at the exchange, of a plurality of cord circuits at the exchange adapted to be connected to the 130

said multiple contacts to answer a call originating at the substation of the said line, marginal controlling apparatus for each of the said cord circuits, an operator's circuit 5 adapted to be associated with each of the said cord circuits, said operator's circuit including a telephone receiver, means including a shunt circuit for the controlling apparatus of a second cord circuit associated 10 with a calling line controlled by the controlling apparatus of a first connected cord circuit to the said telephone line, to prevent the operation of the said second controlling apparatus, and means responsive to the actuation 15 of said controlling apparatus in the first connected cord circuit to apply through contacts of the associated multiple jack of the line a source of tone current to the operator's receiver associated with the second connected cord circuit, at the time having its 20 controlling apparatus in an inoperative condition.

3. In a telephone system, the combination with a telephone line extended from a sub- 25 station and terminating at a main station in a plurality of switching terminals, of a plurality of operators' link circuits at the exchange having answering contacts, each adapted to be connected with a set of the 30 said switching terminals, marginal operating means in a first connected link circuit to associate a source of tone current with interconnected contacts of the said switching terminals, said marginal means of a second 35 connected link circuit being normally in operative condition to convey the said tone current to the operator's set for the said second connected link circuit, under the control of the said switching terminals and 40 the said answering contacts of both of the said link circuits.

4. In a telephone system, the combination with a telephone line extended from a sub- 45 station and terminating at a main station in a plurality of switching terminals, of a plurality of operator's link circuits at the exchange having answering contacts, each adapted to be connected with a set of the 50 said switching terminals, means in a first-named circuit to associate a source of tone current with interconnected contacts of the said switching terminals, the said tone associating means causing the connection of the associated operator's set to the talking 55 conductors of the said link circuit, a shunt circuit including the tone associating means of the first connected circuit to maintain the corresponding tone associating means operative in a second connected link circuit in 60 its normal operative condition to convey the said tone current to the operator's set for the said second link circuit.

5. In a telephone system, the combination with a telephone line extended from a sub- 65 station and terminating at a main station in

a plurality of switching terminals, of a plurality of operators' link circuits at the exchange having answering contacts, each adapted to be connected with a set of the said switching terminals, means in a first-named link circuit to associate a source of tone current with interconnected contacts of the said switching terminals, means responsive to the operation of the said tone associating means to cause the connection of 70 the associated operator's set to the talking conductors of the said link circuit, and means responsive to the connection of the said first connected link circuit to the switching terminals of the calling telephone 75 line to disable the tone associating means of second connected link circuit to permit the flow of the said tone current through the operator's set for the said second link circuit. 80

6. In a telephone system, the combination with a main station, a telephone line terminating at the main station in a plurality of terminals, a plurality of cord circuits at the main station, an operator's set associated with each circuit, means to connect the answering end of each cord circuit to a terminal of the said line, and means responsive to the actuation of the first-named means of a first connected cord to convey a 90 distinctive tone current from the first connected cord circuit to a second connected cord circuit through the said line terminals, the said tone current producing an audible tone in the operator's telephone set associated 95 with the second connected cord circuit. 100

7. In a telephone system, the combination of a main station, a plurality of telephone lines leading to the main station and terminating thereat in a plurality of terminals, a 105 plurality of cord circuits at the main station, each provided with an answering terminal, means to connect each cord circuit through its answering terminals to a line terminal and operator's set associated with 110 each cord circuit, means to connect said operator's set to the cord circuit, and means to prevent the connection of an operator's set to a subsequently connected cord circuit, the first-named operator's connecting means 115 controlling the conveying of a tone current from the first cord circuit to the second cord circuit to produce an audible tone in the second operator's telephone set. 120

8. In a telephone system, the combination of a main station and a substation, a telephone line for the said substation terminating at the main station in a plurality of terminals, a plurality of link connecting circuits at the main station, an operator's telephone set associated with each link connecting circuit, means responsive to the connection of a link connecting circuit to one of the said terminals to cause the associated operator's set to be connected with the said link 125 130

5 circuit, multiple contacts in the said terminals, the said operator's set connecting means applying when actuated a fluctuating tone current to the said multiple contacts, and means responsive to the subsequent connection of a second link circuit to a telephone line to convey the said tone current to the second operator's telephone set.

9. In a telephone system, the combination 10 with a telephone line extended from a substation and terminating at a main station in a plurality of switching terminals, of a plurality of operators' link circuits at the exchange having answering contacts, each 15 adapted to be connected with a set of the said switching terminals, means in a first named circuit to associate a source of tone current with interconnected contacts of the said switching terminals, means responsive 20 to the operation of the said tone associating

means to cause the connection of the associated operator's set to the talking conductors of the said link circuit, and means responsive to the connection of the said first connected link circuit to the switching terminals of the calling telephone line to disable the tone associating means of a second connected link circuit to permit the flow of the said tone current through the operator's set for the said link circuit, said operator's 25 connecting means of the second connected cord circuit being under the control of the said disabling means, said disabling means also disabling the said operator's connecting means of the said second connected cord 30 circuit.

In witness whereof I hereunto subscribe my name this 7th day of Nov., A. D. 1917.

HARVEY L. HARRIS.
